FOREIGN PATENT DOCUMENTS

EP 1138399 A2 * 10/2001

Primary Examiner—Alan P. Douglas*Assistant Examiner*—Lavone D. Tabor(74) *Attorney, Agent, or Firm*—Kagan Binder, PLLC(57) **CLAIM**

The ornamental design for a handle, as shown and described.

DESCRIPTION

FIG. 1 is a perspective view of the handle of the present design;

FIG. 2 is a left side elevational view of the handle of FIG. 1;

FIG. 3 is a right side elevational view of the handle of FIG. 1;

FIG. 4 is a front elevational view of the handle of FIG. 1; FIG. 5 is a rear elevational view of the handle of FIG. 1; FIG. 6 is a top plan view of the handle of FIG. 1; and, FIG. 7 is a bottom plan view of the handle of FIG. 1.

The broken line portions of the drawings are for illustrative purposes only and form no part of the claimed design.
